UNITED STATES PATENT OFFICE

2,034,924

HAT STAND OR RACK

David Simon, Philadelphia, Pa.

Application October 10, 1935, Serial No. 44,336

1 Claim. (Cl. 211—33)

The principal object of the present invention is to provide an attractive and comparatively inexpensive hat rack or stand in which the head, 5 that supports the hat, can readily be arranged in various positions.

Another object is to improve the means for connecting the head that supports the hat with the rod that projects from the stand.

10 Other objects of the invention will appear from the following description at the end of which the invention will be claimed.

Generally stated, the invention consists in a head adapted to enter the crown of the hat and 15 a rod for supporting the head. The head and rod are connected by a fitting which includes a tubular portion for receiving the end of the rod and a ring for connection with the head and a single shank capable of being readily bent to position 20 the head and rod at various angles or at a right angle as may be described.

The invention also consists in the improvements to be presently described and finally claimed.

25 Referring to the drawing,

Figure 1 is an elevational view partly in section illustrating features of the invention.

Figure 2 is a top or plan view of parts shown in Figure 1.

30 Figure 3 is a view similar to Figure 1 illustrating a modification; and

Figure 4 is a perspective view of some of the parts shown in Figure 3.

Referring to the drawing, and more particularly to Figures 1 and 2, 1 is a tubular body adapted for the reception of the end of the rod 2. 3 is a ring to which the head is secured. 4 is a

single shank integral with the tubular body 1 and the ring 3. The ring, shank and tubular body are shown as constructed of a single continuous wire. The head 5, which is adapted to enter and support the crown of a hat, is of generally dished form and it may be made of any appropriate material; for example, of cardboard. Use may be made of an eyelet or grommet as a means for clamping the ring 3 and the head 5 together.

Evidently the head 5 may be arranged at any desired inclination with respect to the rod 2 by simply bending the shank 4. In some cases the rod 2 projects at an inclination from the 15 pole or tree and in that case the parts assume the positions shown in Figure 1. However, if the rod 2 projects vertically from a base the shank 4 can be bent readily in such a way that the head 5 is horizontal.

The construction and mode of operation of the modifications shown in Figures 3 and 4 are as above described except that the tubular body 1^a, the single shank 4^a, and the ring 3^a are stamped from a single piece of sheet metal.

I claim:

In a hat stand or rack having a supporting rod, the combination of a head adapted to enter the crown of a hat, a single tubular body adapted for application to the end of the rod, a ring to 30 which the head is secured and a single shank integral with the ring and tubular body and bendable to permit the tubular body to be variously positioned in respect to the head, and grommet means for fastening the ring and head together.

DAVID SIMON.
